UNITED STATES PATENT OFFICE.

WILLIAM C. TREGONING, OF BRIDGEPORT, CONNECTICUT.

SNAP-SWITCH.

SPECIFICATION forming part of Letters Patent No. 720,858, dated February 17, 1903.

Application filed July 5, 1902. Serial No. 114,344. (No model.)

To all whom it may concern:

Be it known that I, WILLIAM C. TREGONING, a citizen of the United States, residing at Bridgeport, in the county of Fairfield and State of Connecticut, have invented certain new and useful Improvements in Snap-Switches, of which the following is a specification.

This invention relates to a push-button-oscillating snap-switch.

The object is to provide a simple, durable, and efficient single-button switch of this nature.

The invention is represented in the accompanying drawings as designed for a pendent push-button switch; but it is equally applicable to other designs of these switches.

Figure 1 is a side elevation, on enlarged scale, of a pendent push-button switch embodying the invention. Fig. 2 is a view with the shell removed and the receptacle cut in section, showing the mechanism in side elevation with the parts in the positions occupied when the circuit is closed. Fig. 3 is a plan of the receptacle and the mechanism shown in Fig. 2. Fig. 4 is an elevation of the mechanism looking at the side opposite from that shown in Fig. 2, with the pole-piece omitted; and Fig. 5 shows detailed perspective views of parts of the mechanism.

The shell 1 may be spun of brass or similar sheet metal in two parts and screwed together. The receptacle 2, containing the mechanism, is preferably formed of porcelain. The supporting-plate 3 has perforated feet 4, by means of which it is fastened in position in the receptacle, and it has a perforated hub 5, projecting from one side. An arbor 6 extends through the hub, and fixed to the arbor on one side of the supporting-plate is a plate 7. This plate has a wedge 8, on each side of the base of which is a socket 9, and it has a lug 10, projecting from one edge over the edge of the supporting-plate. Loose on the arbor 6 at the end of the hub is a plate 11, to which the insulated pole-piece 12 is fastened. Projecting from the pole-plate toward the wedge-plate is a lug 13. The pole-plate lug 13 is arranged to extend just inside of the wedge-plate lug 10. A spring 14 is wound about the supporting-plate hub, so as to have an end

projecting each side of the two overlapping lugs. Two shoulders 15 are made on the outer end of the supporting-plate to form steps for determining the movement of the 55 lugs. The push-bar 16 is movable between the legs of the supporting-plate and has a push-button 17. A spring 18 is arranged on the bar so as to normally press the button outwardly. Jointed to the push-bar, so as to extend inwardly from the end toward the axis of the wedge-plate, is a finger 19. The end of this finger is preferably provided with a roll 20, and it is held in alinement with the bar by a spring 21. A block 22 is attached 65 to the push-bar on the other side of the support from the spring-finger. This block assists in holding the push-bar in position and guiding it in its movement in and out. For a portion of its movement with the push-bar 70 the block 22 extends into the path of a lug 23, that projects from the pole-plate. When the button is pushed in by the thumb, the roll on the end of the finger attached to the push-bar engages one side of the wedge and is guided 75 into the socket at the base of the wedge and one side of the arbor of the wedge-plate, the finger yielding to allow this. The continued inward movement of the push-button then through the bar, finger, and roll oscillates the 80 wedge-plate, so that its lug pressing against one end of the spring puts the spring under tension. The other end of the spring pressing against the pole-plate lug tends to throw the poles; but the pole-plate 11 cannot move until the push-bar has been pushed inwardly so far that the block 22, which it carries, is moved out of the path of the stop-lug 23 on the pole-plate. When the stop-block has been carried out of the path of the pole-plate 90 lug, the pole-plate is free to move. By this time the spring has been made so tense that it throws the pole-plate and poles violently. When the thumb is removed, the spring 18 pushes out the button. As the bar moves 95 outwardly the finger alines itself and remains in position to engage the other side of the wedge the next time the button is pushed in.

In the drawings a switch with a single pole is illustrated. Of course double poles can be 100 attached to the pole-plate and thrown in the manner described without changing the mech-

anism. Any form of stationary contacts that is desired may be employed for the terminals of the circuits.

By means of this simple construction one push inwardly on the button oscillates the poles to one position, and the next push on the button, which has been returned by its spring, oscillates the poles in the opposite direction for opening and closing the circuit.

10 The mechanism is compact and durable and the parts are simple to manufacture and assemble.

I claim as my invention—

1. A snap-switch having a support, a pole-plate loosely mounted on the support, a wedge-plate loosely mounted on the support, a spring held by the support and having both ends engaging a part of the pole-plate and a part of the wedge-plate, a push-bar, and a yielding finger on the push-bar adapted to engage and move the wedge-plate, substantially as specified.

2. A snap-switch having a support, a pole-plate loosely mounted on the support, a wedge-plate loosely mounted on the support, a spring held by the support and having both ends engaging a part of the pole-plate and a part of the wedge-plate, a push-bar, a finger loosely connected with the push-bar and adapted to engage and move the wedge-plate, a spring for thrusting the push-bar outwardly, a spring for normally holding the finger in alignment with the push-bar, and a block carried by the push-bar and adapted to hold the pole-plate from movement until the wedge-plate has been moved sufficiently to make the spring tense, substantially as specified.

3. A push-button switch having a support, a pole-plate loosely mounted on the support, a wedge-plate loosely mounted on the support, a spring held by the support and having its ends engaging opposite sides of lugs projecting from the pole-plate and from the wedge-plate, a push-bar, a finger projecting from the push-bar and adapted to engage and move the wedge-plate, a block mounted on the push-bar and a lug projecting from the pole-plate and adapted to engage with the block during a part of its movement, substantially as specified.

4. A push-button switch having a receptacle, a support secured in the receptacle, a pole-plate loosely mounted on the support, a wedge-plate loosely mounted on the support, a spring held by the support and having its ends engaging opposite sides of lugs projecting from the pole-plate and from the wedge-plate, a push-bar movable toward and from the axis of the pole-plate and wedge-plate, a yielding finger projecting from the push-bar toward the axis of the pole-plate and the wedge-plate and adapted to engage and move the wedge-plate, a spring for normally holding the finger in alignment with the push-bar, a block mounted on the push-bar, a lug projecting from the pole-plate and adapted to engage with the block during a part of its movement and a cover for the receptacle, substantially as specified.

WILLIAM C. TREGONING.
